DAMPER CONTROL FOR STOKERS

John Roland, Indianapolis, Ind., assignor to
 Schmitzer-Cummins Company, Indianapolis,
 Ind., a corporation

Application March 2, 1933, Serial No. 659,321

3 Claims. (Cl. 137—153)

This invention relates to an automatic damper control, particularly adapted for use with furnace stokers and the like.

In connection with the usual furnace stokers there is a motor-driven fan which produces a forced draft through an air conduit leading to the fire pot, which fan usually operates during all or a portion of the time that the fuel is being mechanically fed therein. Also during non-feeding of the fuel there is a natural draft through such conduit which facilitates the burning of the fuel. As a result thereof, the fuel may be too rapidly consumed under certain conditions. During mild temperatures when the fuel is intermittently fed during short periods of time, so as to maintain a low or kindling fire in the fire pot, an excessive amount of air is forced therethrough, which quickly consumes the fuel. In addition thereto, and during the non-feeding periods, the natural draft continues to consume the fuel more rapidly than required. This sometimes results in the fire being burned out between the time of the last feeding and the next feeding of fuel. The furnace then becomes dead and must be rekindled in addition to quantities of unburned fuel being fed into the fire pot.

It is the object of this invention to automatically control both the forced and natural drafts in accordance with heat requirements and the character of the fuel bed in the fire pot. The ultimate object of the automatic control is principally to retard consumption of the fuel during non-feeding periods to maintain a kindling or pilot fire in the furnace over a longer period of time when there is no heat requirement. This is accomplished by not only cutting down the forced draft during the feeding for kindling maintenance, but by closing the natural draft during the intervals between feedings.

The above is accomplished by providing a butterfly type of valve in the air conduit which normally is in closed position, but which may be moved to open position or partially open position by static pressure created in the conduit. Thus, during substantial periods of heat requirement when the fuel is continuously fed to the fire box and thereby becomes packed therein, and it is desirable to produce the maximum forced draft, the current of air delivered by the fan strikes the compact bed of fuel and thereby raises the static pressure in the conduit, resulting in the valve being opened so as to permit the maximum air flow to the fuel. When there is little or no fuel being fed into the fire bed, the air passage through the bed is more open so that

the current of air freely passes therethrough, reducing the static pressure in the conduit, which results in the valve being wholly or partially closed to cut off the air supply and, therefore, prevent the fuel from being too rapidly burned.

This is accomplished by providing a pressure-actuated member connected with the valve and mounted on the air conduit for moving said valve to its maximum open position when the pressure thereon is increased and permitting said valve to approach closed position as the pressure is decreased.

The full nature of the invention will be understood from the accompanying drawings and the following description and claims:

In the drawings Fig. 1 is a diagrammatic illustration of a furnace showing a fire pot and draft conduit with a valve control mounted thereon. Fig. 2 is a sectional view through a portion of the draft conduit and valve control showing the valve in open position. Fig. 3 is the same as Fig. 2 with parts removed, showing the valve in closed position. Fig. 4 is a section on the line 4—4 of Fig. 2. Fig. 5 is a central vertical section through a modified form of valve control shown in open and fully operative position. Fig. 6 is a section taken on the line 6—6 of Fig. 5, with the parts in partially operative position.

In the drawings there is illustrated a furnace 10 having the usual fire pot 11 containing a bed of fuel 12, the fuel being forced therein by an under feed stoker of the usual type from the fuel hopper 13. The fuel feed 13a and the forced draft are operated from the usual electric motor 14. Driven by the motor 14 there is a centrifugal fan 15 contained within a fan housing 16 connected with an air conduit 17 leading to the fire pot 11 for delivering thereto air by forced or natural draft.

Mounted within the air conduit 17 there is a draft control including a frame 18 adapted to extend into and lie adjacent the walls of the conduit. Pivotedly mounted on said frame there is a valve 19 formed of a plate of substantially the form as the cross sectional area of the conduit, said plate being provided with slightly bent end portions 20 and 21. On one side of said plate there is a dependent counterweight 22, and on the other side thereof there is a bracket 23 to which a control rod 27 is loosely connected. The frame 18 is secured to and supported by a housing 28. Said housing is mounted over an opening 29 formed in the top of the conduit, through which opening the frame 18 and rod 28 extend. The housing is provided with a saddle 30 by which

it is secured over the conduit in fixed relation.

Closing the lower end of the housing 28 and sealed therein there is an upwardly-extending thimble 31 which acts as a guide for the rod 27,

- 5 the walls of the thimble being spaced from the walls of the housing. The rod 27 extends freely through an aperture 32 in the dome-shaped top of the thimble to permit air to freely pass through the top thereof. Mounted over and about the 10 thimble there is a plunger or cup 33 provided with a dome 34 adapted to fit over the dome-like top of the thimble 31. The sides of the cup extend well down between the thimble and housing and the edge of the open bottom thereof is immersed 15 in a bath of oil, indicated at 35. The oil level which at all times extends above the bottom of the cup is maintained by the filler inlet 36. The cup 33 is provided with a vent opening 37 in the upper portion thereof. The rod 27 extends 20 through the top of said cup and is sealed thereto so as to be air tight. Said rod also extends freely through an aperture 38 in the top of the housing and is provided on the upper free end thereof with an indicator button 39.
- 25 In operation, assuming that the fuel 12 is tightly packed in the fire pot 11, and is being continuously fed therein under heat requirement conditions, the resistance to the passage of air through the fuel will create a relatively high static 30 pressure in the conduit 17. This will cause air to be forced into the thimble 31 and through the aperture 32 into the cup 33, creating the same pressure therein. The air not being able to escape from the cup by reason of the oil seal, will 35 tend to raise said cup in order to increase the capacity thereof. Upon the cup being forced upwardly by the air pressure, the stem 27 will be carried therewith to raise that portion of the valve to which it is connected, whereupon the 40 valve will be moved toward or into its open position, as illustrated in Figs. 2 and 4. Thus, the draft conduit 17 will be free of obstruction by the valve.

When the heat requirement decreases and relatively little fuel is fed or packed into the fuel bed, there will be less resistance to the flow of air through the fuel so that the static pressure in the conduit will drop and no longer tend to raise the cup 33 and open the valve. The drop 45 in static pressure will permit the cup 33 to drop by gravity so as to tend to close the valve. The position of the valve will thereupon be balanced at or near closed position, depending upon variation of the static pressure, which in turn will depend on the variation of resistance to the 50 passage of air through the fuel bed.

55 Thus it will be understood that the quantity of air driven through the fuel bed by the fan, or fan capacity, will be automatically maintained substantially constant irrespective of variations in the resistance to its passage created by the packing of the fuel, since a balance is maintained between the resistance of the fan and fuel, i. e., as the fuel resistance increases, the valve resistance decreases and vice versa.

60 When no heat is required and the stoker is merely operated to maintain a kindling or pilot fire, the passage of air will be so freely permitted through the fuel bed as to eliminate any static 65 pressure in the conduit so that the cup 33 will drop to closed position, as shown in Fig. 3, whereupon the valve will be completely closed and substantially cut off both the forced draft and natural draft. This substantial elimination 70 of either forced or natural draft will be conducive

75 to the slowest possible burning of the fuel, whereby the danger of its being consumed and the fire extinguished between operations of the stoker will be eliminated.

By slightly bending the ends of the valve plate, indicated at 20 and 21, the automatic action of the valve is facilitated. This is also assisted through the medium of the counterbalance weight 22. Furthermore, a stop member, such as is indicated at 40, may be mounted upon the frame 10 18 to limit the swinging action of the valve to open position, its swinging action to closed position being limited by engagement with the bottom and top of the frame.

Pivotal mounted over the top of the housing 15 28 there is an adjusting rod 41 having a handle 42 movable to various positions in respect to a plate 43. Said rod is provided with a U-shaped end 44 which, when moved to its upper position, as illustrated in Fig. 2, will limit the downward 20 movement of the rod 27 and, therefore, prevent the full closing of the valve. When it is moved to the extreme lower position, as shown in Fig. 3, it will permit the full drop of the rod and complete closing of the valve.

25 In the modified form of valve control illustrated in Figs. 5 and 6, the valve 118 is provided with a slightly bent end 121 and a bracket 123 is connected to the plunger or disk 133 by a control rod 127. The plunger 133 conforms substantially 30 to the cross sectional area of the housing 128 so as to move upwardly therein under air pressure and downwardly by gravity. Rotatably mounted over the closed upper end of the housing 128 there is a rotatably adjustable control cap 138 35 having downwardly extending flanges 140 closely fitting the upper side walls of the housing and provided with a plurality of apertures 141 adapted to be moved in and out of registry with the apertures 142 formed in the housing. Secured on the 40 outer side of the housing, there is a corrugated plate 143 against which an adjustable hand lever 144 engages for setting a control adjustment rod 145 which extends diametrically through the housing so as to be rotatably supported therein. 45 Said control rod is provided with a U-shaped bend 146 intermediate the sides of the housing and passing about the rod 127.

50 This type of control operates upon the same principle and for the same purpose as the type previously described, excepting that the resistance to its upward or opening movement may be varied and adjusted by rotation of the cap 138 to vary the extent of registry of the apertures 141 and 142. When said apertures are closed, 55 assuming there can be no air leakage therethrough, the valve is inoperative, since the static pressure will be the same on both sides of the plunger 133. However, with the apertures open or partially open, so that the air may escape 60 therethrough, there will be a differential pressure, whereby the pressure on the underside of the plunger may be greater than on the upper side so as to raise the plunger and open the valve. However, when the static pressure in the conduit 17 drops to atmospheric pressure, then there 65 will be an equalizing of pressure such as to permit the plunger to drop by gravity and close the valve. By adjusting the registry of the apertures, a greater or less static pressure may be required to open the valve, as will be clearly understood from the above.

70 By moving the rod 145 about its pivotal mounting, the U-shaped portion 146 may be raised or lowered into or out of the way of the plunger. 75

Thus, by moving it to its extreme upper position, the plunger will be restricted in its downward movement so that the valve will at no time be entirely closed, but remain partially open. The extent of the closing of the valve may, therefore, be varied, depending upon the position of the rod, its lower position being such as to permit the full drop of the plunger and the full closing of the valve.

5 10 The invention claimed is:

- 10 1. A draft regulator comprising a butterfly valve pivotally mounted within a conduit for partially closing said conduit when swung to one position and substantially opening said conduit when swung to another position, a housing open to said conduit, a plunger floating in said housing and operatively connected with said valve, said plunger and valve being so positioned with respect to said conduit as to cause said plunger to be lifted by an increase in pressure in said conduit to move said valve to open position and lowered by gravity upon a decrease in said pressure to move said valve to partially closed position, and adjustable means for effecting a resistance to the movement of said plunger and valve toward open position.
- 15 2. A draft regulator comprising a butterfly valve pivotally mounted within a conduit for partially closing said conduit when swung to one position and substantially opening said conduit when swung to another position, a housing open to said conduit, a plunger floating in said housing and operatively connected with said valve,

20 25 said plunger and valve being so positioned with respect to said conduit as to cause said plunger to be lifted by an increase in pressure in said conduit to move said valve to open position and lowered by gravity upon a decrease in said pressure to move said valve to partially closed position, said housing having an aperture therein, and a control cap for varying the area of said opening to control the resistance to the lifting movement of said plunger.

3. A draft regulator for a draft conduit comprising a butterfly valve pivotally mounted intermediate its ends within said conduit so as to partially close said conduit when moved to a vertical position and open the passage thereto when moved to a substantially horizontal position, a housing in communication with said conduit adjacent said valve, a plunger reciprocable within said housing, a connecting rod connecting said plunger and valve and so arranged with respect thereto as to swing said valve to substantially a horizontal position when said plunger is forced upwardly by pressure in the conduit and permit said valve to swing to substantially a vertical position by gravity upon decrease in pressure, said housing having an aperture therein, and a control cap pivotally mounted on said housing for varying the effective area of the aperture therein for varying the effective pressure upon said plunger exerted from within said conduit and housing.

30 JOHN ROLAND.
